United States Patent

Des. 238,638

Patented Feb. 3, 1976

238,638

DISPENSING CONTAINER

Thomas C. Fischer, 238 E. Westplains,
Gretna, Nebr. 68028

Filed May 6, 1974, Ser. No. 467,069

Term of patent 14 years

Int. Cl. D23—02

U.S. Cl. D6—95

FIG. 1

FIG. 2

FIG. 3

FIG. 5

FIG. 4

FIG. 1 is a perspective view of a dispensing container showing my new design;

FIG. 2 is a side elevational view thereof taken from the right side of FIG. 1;

FIG. 3 is a partial bottom plan view thereof, with the stand omitted for ease of illustration.

FIG. 4 is a rear elevational view thereof; and

FIG. 5 is a partial front elevational view of a modified embodiment wherein the lever of the preferred embodiment has been replaced by a crank.

I claim:

The ornamental design for a dispensing container, substantially as shown and described.
